DESCRIPTION

FIG. 1 is a perspective view of a cut oval shaped vacuum pouch showing our new design;

FIG. 2 is a top view, the bottom view being a mirror image thereof;

FIG. 3 is a front view thereof;

FIG. 4 is a rear view thereof; and,

FIG. 5 is a right side view, the left side view being a mirror image thereof.

The broken lines shown in the drawings are for illustrative purposes only and form no part of the claimed design.
